VEHICLE LIFT

Gary L. Kincaid, St. Joseph, Mo., assignor to Gray Manufacturing Company, Inc., St. Joseph, Mo.

Filed Mar. 23, 1970, Ser. No. 22,025

Term of patent 14 years

Int. Cl. D12—05

U.S. Cl. D41—1

FIG. 1 is a perspective view of the vehicle lift;
FIGS. 2 and 3 have been shown with the handle fore-shortened for convenience of illustration.

I claim:

The ornamental design for a vehicle lift, as shown and described.
